CLAIM

The ornamental design for a shoe sole, as shown and described.

DESCRIPTION

FIG. 1 is a left side elevational view of a shoe sole showing my new design;

FIG. 2 is a right side elevational view thereof;

FIG. 3 is a bottom plan view thereof;

FIG. 4 is a front elevational view thereof; and

FIG. 5 is an elevational view of the rear end, the fore portions that would be visible being omitted for clarity of illustration.

The broken line showing of a shoe upper in FIGS. 1-5 and the area within are environmental only and form no part of the claimed design.
